UNITED STATES PATENT OFFICE

MARTIN KAHR, OF FRANKLIN, PENNSYLVANIA

INTERNAL-COMBUSTION ENGINE

Original application filed March 5, 1926, Serial No. 92,573. Divided and this application filed May 14, 1928. Serial No. 277,676.

This invention relates to internal combustion engines, and while certain features of the invention are susceptible of embodiment in other types of engines, it has particular reference to oil engines, especially engines of the Diesel or semi-Diesel type. While oil engines embodying the present invention are capable of a wide variety of uses, reference will be made, in order to illustrate 10 novel features and advantages of the invention, to the particular utility of an engine of this type in oil field service, but it is to be expressly understood that the invention is not restricted to an engine so employed.

15 This application is a division of the co-pending application Serial No. 92,573, filed March 5, 1926, by the present applicant.

The type of two-cycle internal combustion engine herein contemplated is what is usually termed a valveless engine and comprises an elongated cylinder with a piston reciprocatively mounted therein; one end of said cylinder forms a pump-chamber, and the other end the combustion-chamber.

25 During the operation of the engine, either air or a mixture of gas and air is drawn into the pump-chamber by the action of the piston, from whence it is transferred to the combustion-chamber wherein it is compressed, ignited, expended and released from said combustion-chamber at the end of the expansion stroke through a piston controlled port.

In the ordinary three-port type of two-35 cycle engine, the admission of gas to the pump chamber as well as the by-passing of gas from the pump chamber to the cylinder, and the exhausting of the expanded gases, are all timed and controlled by the piston 40 itself opening and closing ports in the side walls of the cylinder, and since the inlet port to the pump chamber is not uncovered by the piston until near the end of its stroke, the in stroke of the piston is opposed by a 45 progressively increasing vacuum in the pump chamber; moreover since the time for admission of the charge is short, a full charge cannot ordinarily be obtained. Further losses in efficiency may be caused by a 50 restricted area of the inlet port or a speed

of the engine that is higher than that contemplated by the designer of the engine when proportioning said port, thus producing a rarefied charge in the pump chamber,—that is to say a charge having less 55 than normal atmospheric pressure. When such a rarefied charge is transferred to the combustion chamber, it does not produce a complete scavenging of the products of combustion from said combustion chamber, thus 60 causing a reduced power output of the engine.

It is an object of the present invention to provide an oil engine of the two-cycle type in which loss of efficiency due to high 65 vacuum in the pump chamber is avoided.

More particularly it is an object of this invention to provide an oil engine with means for limiting the drop in pressure in the pump chamber during the intake of the 70 air, so as to avoid power losses and improve the conditions of combustion of the fuel. Other objects will appear as the description of the invention proceeds.

The invention is capable of receiving a 75 variety of mechanical expressions, one of which has been shown on the accompanying drawing, but it is to be expressly understood that the drawing is for purposes of illustration only, and is not to be construed as a 80 definition of the limits of the invention, reference being had to the appended claims for that purpose.

Referring in detail to the drawing, where 85 in the same reference characters are employed to designate corresponding parts in the several figures:

Fig. 1 is an axial section through an engine cylinder and a portion of the pump chamber of an internal combustion engine 90 embodying the present invention;

Fig. 2 is an axial section through an air valve embodied therein; and

Fig. 3 is a face view of said air valve.

Referring first to Fig. 1, the invention is 95 shown as embodied in an oil engine the cylinder wall of which is designated 20. Said engine is illustrated as provided with the usual or any suitable water-jacket 21, and mounted within the cylinder 20 is the usual 100

liner 22 of any suitable construction, the joint between said cylinder wall 20 and the liner 22 being sealed by a stuffing box 23.

Within the cylinder is a piston 24 of any suitable construction mounted on the piston rod 25. Said piston is open at its end adjacent the crank shaft and provides with the cylinder casing the usual pump chamber 26 of a two-cycle internal combustion engine. An air inlet port is indicated at 27 and communicates with the pump chamber 26 through the port 28 in the cylinder wall 20 and the liner 22. A transfer port is shown at 29 and the exhaust conduit is indicated at 30. The inner end of the cylinder is closed by a water-jacketed head 31 of any suitable construction which is interiorly formed to provide a combustion chamber 32.

In conformity with the present invention an auxiliary air valve is provided in the pump chamber 26 of the engine so as to prevent an excessive drop in pressure in said chamber during the period when the piston is moving toward the head of the cylinder. Referring to the drawing, it will be observed that in the absence of any auxiliary air valve the air port 28 will not be opened until the skirt of the piston 24 has uncovered the same. During this stroke of the piston the piston is pulling against a vacuum in the pump chamber which is continually increasing up to the instant when the air port 28 is uncovered. Hence there is an increasing difference in pressure on the face and the rear of the piston which represents a loss in power. To avoid this loss there is provided an auxiliary air valve which is illustrated at 10 in Fig. 1 and which is shown in detail in Figs. 2 and 3 of the drawing. This auxiliary air valve may be of any suitable construction, and is shown as including a disc 11 of any suitable material which is normally pressed against an apertured wall 12 by means of a plurality of coiled springs 13. Said springs 13 react between said valve disc 11 and a spring retainer 14 which is mounted on a plurality of bolts 15 which project through the apertured wall 12 where they are provided with lock nuts 16. Distance pieces 17 are interposed between the spring retainer 14 and the wall 12. The valve is provided with a housing 18 of any suitable character, being shown as having threaded apertures so that the same may be suitably mounted in the wall in the pump chamber of the cylinder.

The springs 13 are selected of suitable strength so that when a predetermined vacuum, say one pound per square inch, has been created in the pump chamber, said valve disc 11 will open against the tension of said springs and permit the inflow of air into the pump chamber. This admission of air to the pump chamber before the main air inlet port 28 is opened, possesses

numerous advantages, because it not only prevents an undue drop of pressure in the pump chamber, but it also provides a longer period during which air may be drawn into said pump chamber, so that there is a better scavenging of the engine cylinder and better compression and combustion. The main air inlet port may also be decreased in size. Experience has demonstrated that the use of this auxiliary air inlet port has produced about a 10% increase in the power of the engine.

In operation, as the piston starts on its pumping stroke the auxiliary air valve 10 opens as soon as a predetermined drop in pressure is produced in the pump chamber, and further air is introduced through the main air inlet port 28 when the latter is uncovered by the skirt of the piston. During the stroke of the piston in the opposite direction the air thus introduced into the pump chamber is compressed, the escape of air from said chamber being prevented by the closure of the port 28 by the skirt of the piston and by the closure of the valve 10 owing to the internal pressure acting thereon. At the end of this stroke the air is transferred to the opposite end of the cylinder through the transfer port 29 as is usual in internal combustion engines of the two-cycle type, and within said combustion chamber the usual power-developing phases take place.

It will be seen that there is herein provided means for avoiding the power losses caused by high vacuum in the pump chamber, and for securing complete combustion and superior operating efficiency by reason of the uniform full charges of air introduced into the combustion chamber. While the embodiment of the invention illustrated in the drawing has been described with considerable particularity, it is to be expressly understood that the invention is not to be restricted to the embodiment shown and described, as various other embodiments will now suggest themselves to those skilled in the art. Reference is therefore to be had to the claims appended hereto for a definition of the limits of the invention.

What is claimed is:

1. In an internal combustion engine, in combination with the engine cylinder and pump chamber, a piston in the cylinder, a main air inlet port for the pump chamber controlled by the movement of the piston, an auxiliary air inlet port communicating with the pump chamber, and a valve controlled only by the pressure in said pump chamber and controlling said auxiliary air inlet port, said valve being adapted to be opened independently of said piston upon a predetermined drop of pressure in said pump chamber.

2. In an internal combustion engine, in

- combination with the engine cylinder and pump chamber, a piston in the cylinder, a main air inlet port for the pump chamber controlled by the movement of the piston, an auxiliary air inlet port communicating with the pump chamber, a valve member cooperating with said auxiliary air port, and controlled only by the pressure in said pump chamber, and spring means for operating said valve member and yielding upon a predetermined drop of pressure in said pump chamber and independently of the position of said piston to permit the opening of said auxiliary air port.
- 10 3. In an internal combustion engine, in combination with the engine cylinder and pump chamber, a piston in the cylinder, a main air inlet port for the pump chamber controlled by the movement of said piston, an auxiliary air inlet port communicating with the pump chamber, and a valve operating independently of the position of said piston for opening said auxiliary air inlet in advance of the opening of said main air inlet.
- 15 4. In an internal combustion engine, in combination with the engine cylinder and pump chamber, a piston in the cylinder, a main air inlet port for the pump chamber, and valve means in the pump chamber of said engine controlled only by the pressure in said pump chamber for preventing more than a predetermined small drop of pressure therein.
- 20 5. In an internal combustion engine, in combination with the engine cylinder and pump chamber, a piston in the cylinder, a main air inlet port for the pump chamber opened and closed by said piston, and means in the pump chamber of said engine controlled only by the pressure therein for admitting air thereinto for a portion of the stroke of said piston and prior to the opening of said main air inlet port.
- 25 45 In testimony whereof I have signed this specification.
